VISE

William Maki, St. Maries, Idaho

Application September 23, 1937, Serial No. 165,385

2 Claims. (Cl. 81—25)

This invention relates to a vise.

It is aimed to provide a novel construction of vise capable of quick opening and provided with a novel yoke and pawl to assist in the adjustment, and also preferably provided with a cutting attachment and a punch press.

The more specific objects and advantages will become apparent from a consideration of the description following taken in connection with the accompanying drawing illustrating an operative embodiment.

In said drawing:

Figure 1 is a view in side elevation of the vise;

Figure 2 is an edge elevation of the vise taken substantially on the plane of line 2—2 of Figure 1;

Figure 3 is a vertical section taken on the plane of line 3—3 of Figure 2, and

Figure 4 is a horizontal sectional view taken on the plane of line 4—4 of Figure 1.

Referring specifically to the drawing wherein like reference characters designate like or similar parts, 10 designates a vertical relatively stationary jaw which is extended as at 11, to form a means whereby it may be attached to a bench or other support. An arm 12 extends forwardly from the jaw member 10 and a jaw member 13, complementary to that at 10 is pivotally connected at 14 to said arm 12. A leaf spring 15, fastened as at 16 to the jaw 10 bears against the jaw 13 and tends to open it at the gripping portion 17, away from the gripping portion 18 of the jaw 10.

A U-shaped metallic yoke or strap 19 surrounds the jaws 10 and 13 providing a bar on each side thereof and such jaws are cutaway or grooved as at 20 and 21, in their sides, to mount such yoke. The terminals of the yoke are joined by a rod or bolt 21' on which the eccentric 22 of a lever 23 is pivoted, the eccentric engaging in a socket or cutaway portion 24 of the jaw 13. A leaf spring 25 is pivoted at 26 to the jaw 13 and it bears against a pin or abutment 27 on the yoke, and is tensioned so as to maintain the periphery of the eccentric 22 in engagement with the wall of the socket 24.

Said yoke 19 in its under edge is provided with teeth or serrations as at 28 and the same are engageable by a pawl 29. The pawl 29 rests in a notch 30 of the jaw 10 and it is urged toward the vertical by means of weights 31 carried by fingers 32 extending from the pawl 29 and disposed one on each side of the jaw 10. The pawl thus removably rests in the recess 30. The pawl also has projections 33 extending therefrom and between the side members of the yoke 19 as a further guard against displacement accidentally of the pawl.

It will thus be realized that the yoke and pawl may be manually operated so as to engage the pawl 29 in any of the teeth or serrations 28 according to the work or adjustment desired and that for the final or positive clamping action, the lever 23 may be operated so that the eccentric will bear against the recess 24 and cause the jaw 13 to close against the jaw 10 at the gripping portions 17 and 18.

The jaws may also be used to operate cutters 10 and in this connection, co-acting cutting elements 34 extend one from each of the jaws 13 and 10.

The said jaws may also be used to operate as a punch press and in this connection the complementary elements 35 and 36 of a conventional punch press are connected to the jaws 13 and 10, respectively.

Various changes may be resorted to provided they fall within the spirit and scope of the invention.

I claim as my invention:

1. Apparatus of the class described comprising a pair of jaws, means mounting one of the jaws for pivotal movement relatively to the other, a yoke surrounding the jaws, teeth on the yoke, a pawl mounted by one of the jaws engageable with the teeth, means mounted by the yoke engageable with the other jaw to tighten the jaws, the jaw carrying the pawl having a recess in which the pawl is loosely disposed, means preventing lateral displacement of the pawl, comprising fingers disposed on opposite sides of the jaw having the recess, said fingers being weighted to urge the pawl into engagement with the teeth, and projections on the pawl disposed between the side members of the yoke.

2. Apparatus of the class described comprising a pair of jaws, means mounting one of the jaws for pivotal movement relatively to the other, a yoke surrounding the jaws, teeth on the yoke, a pawl mounted by one of the jaws engageable with the teeth, means mounted by the yoke engageable with the other jaw to tighten the jaws, the jaw carrying the pawl having a recess in which the pawl is loosely disposed, means preventing lateral displacement of the pawl, comprising fingers disposed on opposite sides of the jaw having the recess, said fingers being weighted to urge the pawl into engagement with the teeth, cam means carried by the yoke and operable to close the jaws, and a spring means urging the cam into engagement with the jaw adjacent thereto and having abutment with the yoke.

WILLIAM MAKI. 55
